Primary Examiner — Philip S Hyder*Assistant Examiner* — Darlington Ly(57) **CLAIM**

The ornamental design for a bicycle stem, as shown and described.

DESCRIPTION

FIG. 1 is a top, front and right side perspective view of a bicycle stem illustrating my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom, rear, right side perspective view thereof.

The broken lines in the drawings illustrate portions of the bicycle stem that forms not part of the claimed design.
